SAND PLAYBOX

John M. Zahner, Ogden, Utah

Application February 19, 1946, Serial No. 648,648

4 Claims. (Cl. 222—189)

1

This invention relates to a sand play box, and more particularly to such a device adapted for the amusement and entertainment of children or the like.

A primary object of this invention is the provision of an improved sand play box characterized by a plurality of closable apertures in the base thereof, whereby sand may be permitted to flow from the box through such apertures as desired.

An additional object of the invention is the provision of means whereby the plurality of apertures may be simultaneously opened and closed, and whereby the degree of opening of such apertures may be readily controlled.

Still another object of the invention is the provision of guard means in association with such a device, whereby the fingers of the juvenile user thereof are protected from injury in the opening and closing of the apertures.

Still another object of the invention is the provision of such a device which is sturdy and durable in construction, reliable and efficient in operation, and relatively simple and inexpensive to manufacture and assemble.

Other objects will in part be obvious and in part be pointed out as the description of the invention proceeds and shown in the accompanying drawings, wherein there is disclosed a preferred embodiment of this inventive concept.

In the drawings:

Figure 1 is a top plan view of one form of device embodying features of the instant invention.

Figure 2 is a central longitudinal vertical sectional view of the device.

Figure 3 is a central transverse vertical sectional view of the device.

Figure 4 is a fragmentary bottom plan view of the device, certain concealed portions thereof being indicated in dotted lines.

Figure 5 is a fragmentary perspective view of a constructional detail.

Similar reference characters refer to similar parts throughout the several views of the drawings.

Referring now to the drawings, the device of the instant invention is comprised of a receptacle generally indicated at 10, including side walls 11, end walls 12, and a bottom generally indicated at 13.

The top of the device is open and is covered with a foraminous member 14, such as a fine screen, secured in position by side sheathing strips 15 and end strips 16 which engage overlapping portions 17 of the wire 14 and are held in position, as

2

by brads or nails 18, secured to the side and end walls, respectively.

Reinforcing bolts 19, as best shown in Figure 3, extend transversely between the side walls 15 at suitable spaced intervals. The bolts 19 are provided with heads 20 and washers 21 and 22 on opposite sides of the device, respectively, and held in related assembly, as by means of nuts 23.

Each of the end walls 12 is provided with a suitable handle 24 to facilitate moving of the device.

As best shown in Figure 2, the end portions 12, are fitted into the bottom section 13 in suitable rabbeted portions 25, and as best shown in Figure 3, the side walls 11 are correspondingly seated in rabbets 26 in the sides of the base 13.

Referring back to the base 13, it will be seen that the same is provided with a plurality of apertures 30, the sides of which are beveled, as at 31, to facilitate the free passage of sand therethrough. While in the illustrative embodiment herein shown and described there are three apertures, it is to be understood that the number may be increased or decreased, as desired.

Extending longitudinally of the device and terminating adjacent the beveled sides 31 of the apertures 30 are a pair of sand guide blocks 32 of triangular cross-sectional configuration, adapted to serve not only as guides for the sand to direct 30 the same into the apertures 30, but also as reinforcing members to strengthen the assembly.

Underlying the base 13 are a pair of longitudinally extending guideways 33 provided with rabbeted or channel portions 34, within which are

slidably mounted closure blocks 35 adapted to close the apertures 30. The ends of the channels formed in the blocks 33 are closed by transversely extending members 36 at each end thereof to preclude the complete withdrawal of the closure blocks 35 when moved in a manner to be more fully described hereinafter. Secured to the under side of each of the blocks 35, as by means of brads or nails 37, is a longitudinally extending control rod or strip 38, which extends outwardly

40 from either end of the receptacle 10 in such manner that the end thereof may be grasped to simultaneously slide all of the closure members 35 linearly within the channels 34 of the members 33. Positioned beneath the bottom 13 along the

50 sides thereof and outwardly of the guide members 33 are a pair of block members 40 to the under sides of which is secured a screen 41 adapted to serve as a filter for the sand, and simultaneously to protect the working parts of the mechanism. The screen 41 is secured in position,

as by means of longitudinally extending strips 42 secured to the blocks 40, as by means of nails or brads 43.

The screen 41 also will act as a guard or protector to prevent a child from injuring the fingers during the use of this device or when operating the sand control mechanism.

From the foregoing the operation of the device should now be readily understandable. The receptacle 10 is first filled with sand through the screen 14, thus filtering out all undesirable lumps or other elements, the closure members 35 meanwhile being retained in closed position. When it is desired to permit the sand to flow from the device, the control member 38 is moved longitudinally, thus opening the apertures 30 by movement of the closure members 35 to any desired degree. Obviously, a relatively fine flow of sand may be permitted to fall from the apertures when they are slightly open, or a relatively large volume when completely open. The sand may be permitted to flow to any desired position or location, and added amusement value may be afforded the device by the use of two in conjunction, the sand flowing from one into the other, the first box being placed on a relatively raised device, such as a stand (generally indicated at 50, see Fig. 2), and the position of the boxes reversed when the sand is exhausted from the first box. Equally obviously the flow of sand may be utilized to operate any desired type of sand toy or other apparatus.

The device may be manufactured in any desired size and utilized either for outdoor play or indoor play in association with any conventional type of sand box or similar device, and may be manufactured of any suitable material, although in actual practice wood, such as pine or the like, has been found to be preferable.

From the foregoing it will now be seen that there is herein provided an improved device accomplishing all the objects of this invention, and others, including many advantages of great practical utility and high entertainment value.

As many embodiments may be made of this inventive concept, and as many modifications may be made of the embodiment hereinbefore shown and described, it is to be understood that all matter herein is to be interpreted merely as illustrative and not in a limiting sense.

I claim:

1. In a sand play device, a supporting base provided with a longitudinally extending opening, a foraminous member extending across said longitudinally extending opening and secured to said base, a receptacle having an open top for the insertion of sand therethrough supported on said base, the bottom of said receptacle being provided with a plurality of openings arranged in spaced parallel relation longitudinally thereof, the openings in the bottom of said receptacle being in alignment with the longitudinally extending opening in said base, a plurality of spaced closure members arranged longitudinally of the bottom of said receptacle and mounted on said bottom for movement into and out of closing relation with respect to said openings, and hand-actuable means carried by said closure means and operable adjacent the opposed ends of said receptacle for simultaneously positioning said plurality of closure members at select points of said movement into and out of closing relationship with respect to said openings.

2. In a sand play device, a supporting base provided with a longitudinally extending opening, a

foraminous member extending across said longitudinally extending opening and secured to said base, a receptacle having an open top for the insertion of sand therethrough supported on said base, a second foraminous member extending across the open top of said receptacle and secured thereto, the bottom of said receptacle being provided with a plurality of openings arranged in spaced parallel relation longitudinally thereof, the openings in the bottom of said receptacle being in alignment with the longitudinally extending opening in said base, a plurality of spaced closure members arranged longitudinally of the bottom of said receptacle and mounted on said bottom for movement into and out of closing relation with respect to the openings in said receptacle, and hand-actuable means carried by said closure means for simultaneously positioning said plurality of closure members at select points of said movement into and out of closing relation with respect to the openings in said receptacle.

3. In a sand play device, a supporting base provided with a longitudinally extending opening, a foraminous member extending across said longitudinally extending opening and secured to said base, a receptacle having an open top for the insertion of sand therethrough supported on said base, a second foraminous member extending across the open top of said receptacle and secured thereto, the bottom of said receptacle being provided with a plurality of openings arranged in spaced parallel relation longitudinally thereof, the openings in the bottom of said receptacle being in alignment with the longitudinally extending opening in said base, guide means secured to said bottom and extending longitudinally thereof for directing said sand toward the openings in the bottom of said receptacle, a plurality of spaced closure members arranged longitudinally of the bottom of said receptacle and mounted on said bottom for movement into and out of closing relation with respect to said openings, and hand-actuable means carried by said closure means and operable adjacent the opposed ends of said receptacle for simultaneously positioning said plurality of closure members at select points of said movement into and out of closing relation with respect to the openings in the bottom of said receptacle.

4. In a sand play device, a supporting base provided with a longitudinally extending opening, a foraminous member extending across said longitudinally extending opening and secured to said base, a receptacle having an open top for the insertion of sand therethrough supported on said base, a second foraminous member extending across the open top of said receptacle and secured thereto, the bottom of said receptacle being provided with a plurality of openings arranged in spaced parallel relation longitudinally thereof, the openings in the bottom of said receptacle being in alignment with the longitudinally extending opening in said base, guide means secured to said bottom and extending longitudinally thereof for directing said sand toward the openings in the bottom of said receptacle, a plurality of spaced closure members arranged longitudinally of the bottom of said receptacle and mounted on said bottom for movement into and out of closing relation with respect to the openings in the bottom of said receptacle, stop means carried on the under side of the bottom of said receptacle and engaging at least two of said plurality of closure members for limiting the movement of said closure members for limiting the movement of the latter out of closing relation with respect to

said openings, and hand-actuable means carried by said closure members and operable adjacent the opposed ends of said receptacle for simultaneously positioning said plurality of closure members at select points of said movement into and out of closing relation with respect to the openings in the bottom of said receptacle.

JOHN M. ZAHNER.
